UNITED STATES PATENT OFFICE.

CHARLES B. KIRKHAM, OF BUFFALO, NEW YORK, ASSIGNOR TO CURTISS AEROPLANE AND MOTOR CORPORATION, A CORPORATION OF NEW YORK.

EXHAUST-MANIFOLD.

1,294,475.

Specification of Letters Patent.

Patented Feb. 18, 1919.

Application filed March 26, 1917. Serial No. 157,452.

To all whom it may concern:

Be it known that I, CHARLES B. KIRKHAM, a citizen of the United States, residing at Buffalo, in the county of Erie and 5 State of New York, have invented certain new and useful Improvements in Exhaust Manifolds, of which the following is a specification.

My invention relates in general to internal combustion engines, and more particularly to the provision of a manifold therefor. The various types of manifolds in use at the present time for multicylinder motors are of such construction that they offer 10 quite an appreciable resistance to the free passage of the exhaust gases through them. This resistance is due in a large measure to the skin friction which produces a choking of the gases exhausted from the cylinders, together with abnormal back pressure and a resulting loss of power which is extremely undesirable, particularly in the case of motors which are used in connection with aeronautical work, where maximum power 15 output with minimum weight is of extreme importance.

In order to overcome the above mentioned objections I provide a manifold in which all the conduits forming a part of the manifold are of expanding cross sectional area throughout their length from the inlet to the outlet. In this way the exhaust gases are free to expand as they traverse the length of the conduit thereby greatly reducing the back pressure which would otherwise result from excessive pipe friction.

In addition to providing expanding conduits throughout in the construction of my manifold the main conduit and the several branches which lead therefrom and connect with the separate exhaust ports of the motor cylinders are so arranged that they present quite an appreciable influence in the exhausting of any particular cylinder by 20 reason of the fact that the suction created by the passage of exhaust gases from one cylinder draws the exhaust gases from the succeedingly firing cylinders into the main conduit. Thus it is seen that my invention not only overcomes the objections of back pressure but it also actually induces a more complete exhaustion of the gases from the cylinders.

More particular reference may be had to the accompanying drawings, in which:

55

Figure 1— is an elevation of an airplane upon which my manifold is mounted.

Fig. 2— is a longitudinal section through the manifold of my invention.

Fig. 3— is a plan view of the manifold.

Fig. 4— is a lateral section through a portion of the manifold.

In Fig. 1 the manifold may be represented as comprising a series of inlet conduits 1, 2, 3 and 4, which are designed to connect with the various cylinders of an internal combustion engine. The main body of the manifold, represented as an entirety by 5 is composed of an outer conduit casing 6 to which are connected the branches 1 and 70 4, and an inner conduit casing 7 to which are connected the conduits 2 and 3. This may be more clearly understood by reference to Fig. 3 in which the exact relation of the conduits 6 and 7 is clearly shown. Both 75 these conduits 6 and 7 are provided with a common outlet 8 which is arranged for connection with an exhaust pipe or suitable muffler as desired. It will be noticed that the main conduit casings both inner and 80 outer, as well as the branches which lead therefrom are of constantly expanding cross sectional area for the reasons pointed out in the first part of the specification.

In order for the manifold to operate to 85 the best advantage the firing order of the cylinders in the case of four cylinders exhausting into the manifold should be 1, 2, 4, 3, although several other combinations of firing order may be used, depending on 90 the cylinder arrangement and the arrangement of the branches relative to the main conduits. Assuming, however, that the firing order is 1, 2, 4, 3, it may easily be seen that the cylinder exhausting into conduit 95 No. 1 will force its gases out through the outer conduit casing 6. The exit of these gases from the mouth of the casing 6 into the common outlet 8 produces a suction within the conduit 7. Cylinder No. 2 which 100 fires next is therefore assisted in exhausting by reason of this suction. In the same manner as above set forth the action of the gases issuing from the mouth of the inner conduit 7 into the common outlet 8 will produce a suction in the outer conduit 6 where-

upon the exhaust gases created by the firing of cylinder No. 4 are drawn out. The action of the gases escaping from the conduit 6 as they pass into the common outlet 8 5 will again produce suction in the conduit 7 thereby assisting in the exhaust of the gases created by the firing of cylinder No. 3.

Branches 1, 2, 3 and 4 of the manifold are provided with reinforcing bands 9, 10, 11 10 and 12 in order that they may be suitably attached to the cylinder outlets. The preferable construction of the manifold is steel or other suitable metal which is either welded or brazed so that it is of practically 15 a unified whole. However, other methods of construction may be utilized, the main feature of the invention residing in the fact that the sectional area of the manifold is of constantly increasing value and in the 20 arrangement of the relative parts in such manner that suction will be created in one part by the action of exhaust gases in the preceding parts.

Although I have described the preferred 25 embodiment of my invention, I do not limit myself thereto since various other forms of construction and materials may be used without in any way departing from the spirit of the invention as set forth in the 30 claims.

What is claimed is:

1. In combination with an internal combustion engine, an exhaust manifold comprising an outer conduit and an inner conduit of expanding diameters, and separate 35 connections between the several motor cylinders and the conduits alternately arranged whereby the suction created by one cylinder exhaust assists in the exhausting of the succeedingly firing cylinder. 40

2. In combination with an internal combustion engine, a manifold comprising separate conduits of expanding diameter and of different diameters, the conduit of smaller diameter being inclosed within the other, and connections between the conduits and different motor cylinders whereby the escape of exhaust from the larger conduit assists in the escape of exhaust from the smaller conduit and vice versa. 45

3. A manifold for an internal combustion engine comprising a main inner expanding conduit, a main outer expanding conduit, and connections between the respective conduits and the several motor cylinders so arranged that the suction created by the passage of exhaust gases from one cylinder will assist in the passage of gases from a succeedingly firing cylinder. 50

4. In a multi-cylinder internal combustion engine, in combination with a cylinder bank, an exhaust manifold comprising a pair of conduits of different diameters, one being arranged within the other, connections leading from one of said conduits to a pair of non-adjacent cylinders, and connections leading from the other of said conduits to a pair of adjacent cylinders. 60

In testimony whereof I hereunto affix my signature.

CHARLES B. KIRKHAM.
